UNITED STATES PATENT OFFICE.

HOWARD A. JOHNSON, OF NORFOLK, VIRGINIA.

ROLLING DOOR.

1,345,447.

Specification of Letters Patent.

Patented July 6, 1920.

Application filed May 24, 1919. Serial No. 299,476.

To all whom it may concern:

Be it known that I, HOWARD A. JOHNSON, a citizen of the United States, and residing at Norfolk, Norfolk county, State of Virginia, have invented certain new and useful Improvements in Rolling Doors, of which the following is a specification.

The present invention relates to rolling doors and more particularly to the type comprising metal slats or sections hinged together and adapted to be wound up into a coil at the top of the door.

The principal feature of the present invention resides in the means for securing the top of the door to the wheels of barrels on the head shaft. Other features and objects of novelty will be apparent from the description taken in connection with the drawings in which:

20 Figure 1 is a top plan view of a part of a door constructed in accordance with the present invention; and

Fig. 2 is a sectional elevation taken substantially on the line 2—2 of Fig. 1.

25 Referring to the drawings the numeral 10 indicates the head shaft of the usual construction having secured thereto and spaced therealong the wheels or barrels 11. The closure part of the door is made up of metal sections or slats 12 having their longitudinal edges hinged together in any suitable manner as indicated at 13.

Heretofore the top member 14 of the closure portion of the door has been secured 35 directly to the wheels or barrels by pin fastenings, such as bolts or rivets. This type of fastening may fail either by shearing the pins or the pins crushing through the top member. The shearing strength of the pins

40 may be increased by increasing their diameters but of course there is a limit to the size which may be employed. Likewise the resistance to crushing through the top member also increases with the diameter of the pins, but not so rapidly as the shearing resistance of the pins. Of course the crushing resistance of the top member is also increased if it is made thicker, but the thickness of this top member is limited and should

50 not be much greater than the thickness of the other slats constituting the door closure. It will be apparent, therefore, in order to properly secure the top member to the barrels, a sufficient number of pins must be provided. This means, therefore, that a rela-

tively large number of wheels or barrels must be used to accommodate these pins.

According to the present invention means for securing the top member to the wheels is employed which permits the use of only a small number of wheels and yet gives as strong a fastening as is necessary. This result is accomplished by attaching the top member of the flexible door sections to a bar by means of as many pins as desired, and providing a connection between the bar and wheels which is as strong or stronger than the connection of the top member to said bar. As shown, the wheels 11 have a substantially spiral periphery the beginning of the spiral being indicated at 15 and the end at 16, this latter part having a greater radius than the beginning of the spiral at 15. Between the points 15 and 16 the periphery of the wheel is provided with a flat surface 15' and is formed with a transverse slot 17. An angle iron 18 is disposed with the inner surface of one leg resting on the flat portions 15' of the wheels and the other leg disposed in said slots. The top member 14 of the door is secured to the first mentioned leg of the angle iron by pin fastenings such as bolts 19. It will be observed that as many bolts as desired may be employed as the angle iron is of substantially the same length 75 as the top member 14. Consequently, the top member is secured to the angle iron by fastening means which are strong enough to resist all forces coming on the same. On the other hand, the angle iron being connected to the wheels by having a leg disposed in the transverse slots provides practically an unbreakable connection. Furthermore, as the angle iron extends from end to end of the door and is a rigid member, 80 only a few wheels or barrels are necessary. Although an angle iron has been described as being employed to secure the top member to the wheels, it is obvious that bars of other cross sectional shape might be employed the 85 principal requirement being that the bar have a surface thereof abutting a surface on the wheel to hold it from displacement, due to the pull of the door.

Although a specific embodiment of the invention has been described in detail, it is to be understood that the invention is not thus limited but includes modifications and changes which come within the scope of the appended claims.

Having thus described the invention what is claimed as new and desired to be secured by Letters Patent is:

1. A rolling door construction including in combination, a head shaft, spaced wheels secured to said shaft, each wheel having a transverse slot in its periphery, an angle iron disposed parallel to the shaft with one leg in the slot of the wheels, and a flexible door secured at its upper edge to the other leg of said angle iron.
2. A rolling door construction including in combination, a head shaft, spaced wheels secured to said shaft, each wheel having a transverse slot in its periphery, an angle iron disposed parallel to the shaft with one leg in the slot of the wheels, a flexible door, and pins securing the upper member of the door to the other leg of the angle, the number of pins being greater than the number of wheels.
3. A rolling door construction including in combination, a head shaft, spaced wheels secured to said shaft, each wheel having a transverse slot in its periphery, a bar disposed parallel to the shaft having a projec-

tion seated in the slot of each wheel, and a flexible door secured at its upper edge to said bar.

4. A rolling door construction including in combination, a head shaft, spaced wheels secured to said shaft, each wheel having a transverse slot in its periphery, a bar disposed parallel to the shaft and bearing against the surface bounding one side of said slots whereby said bar is held against movement circumferentially of the wheels, and a flexible door secured at its upper edge to said bar.

5. As an article of manufacture, a wheel or barrel for rolling doors having a spiral peripheral surface, the beginning and end of the spiral being connected by a substantially radial surface and the spiral surface adjacent its point of least radius formed with a transverse slot.

6. As an article of manufacture, a wheel or barrel for rolling doors having a spiral peripheral surface, formed with a transverse slot adjacent the point of least radius.

In testimony whereof I affix my signature.
HOWARD A. JOHNSON.
